UNITED STATES PATENT OFFICE.

JOSEPH S. ISIDOR, OF NEWARK, NEW JERSEY, ASSIGNOR TO THE R. NEUMANN HARDWARE CO., A CORPORATION OF NEW JERSEY.

BAG-FRAME FASTENER.

1,370,748.

Specification of Letters Patent.

Patented Mar. 8, 1921.

Application filed October 7, 1920. Serial No. 415,268.

To all whom it may concern:

Be it known that I, JOSEPH S. ISIDOR, a citizen of the United States, residing at Newark, in the county of Essex and State 5 of New Jersey, have invented certain new and useful Improvements in Bag-Frame Fasteners; and I do hereby declare the following to be a full, clear, and exact description of the invention, such as will enable 10 others skilled in the art to which it appertains to make and use the same, reference being had to the accompanying drawings, and to characters of reference marked thereon, which form a part of this specification.

15 This invention relates, generally, to improvements in frames for traveling and other bags, and locking devices therefor; and, the present invention has reference, more particularly, to a novel and simply- 20 constructed locking or holding catch for bag-frames, in which the locking or holding post or finger extending downwardly from the usual pivoted or hinged operating lever, is located at or near one of the longitudinally extending marginal edges of the 25 top or upper surface of the catch-box or casing, so as to readily coöperate with correspondingly formed slits or openings, with which the hinged frame-sections of the bag- 30 frame are provided, to retain the said frame-sections in their closed relation.

As is well known, in the construction of bag-frames two hinged or pivotally connected frame-sections are employed, the inner frame-section being quite narrow, and that the said narrow frame-section may be provided with a lock-post-receiving slot which is centrally disposed between the longitudinally extending marginal edges of 40 said inner frame-section, the novel bag-frame catch hereinafter more fully described has been devised.

The present invention, therefore, has as its 45 principal object to provide a novel and simply-constructed bag-frame catch of the general character hereinafter set forth; and furthermore, to provide, in connection such catch, the outer and inner frame-sections with correspondingly disposed lock-post-re- 50 ceiving slots, arranged in the respective frame-sections that the latter are not weakened, and also that each frame-section has a continuous marginal edge, thereby providing a neater construction of frame, and enabling the omission of the usual hasps se-

cured to the narrow inner frame-section by being riveted thereto.

Aside from the fact, that by the omission of the usual hasps, the cost of manufacture is reduced, the frame-sections have unobstructed marginal edge-portions, thus, when the bag has been opened, presenting no objectionable obstructions in which the lace on the sleeves of ladies' garments, when the hand is thrust in the bag, can catch and become torn.

Other objects of the present invention not at this time more particularly enumerated will be clearly understood from the following detailed description of the present 70 invention.

With the various objects of the present invention in view, the said invention consists, primarily in the novel bag-frame catch hereinafter set forth; and, the said invention consists, furthermore, in the novel arrangements and combinations of the various devices and parts, as well as in the details of the construction of the said parts, all of which will be more fully described in 80 the following specification, and then finally embodied in the clauses of the claim which are appended to and which form an essential part of the said specification.

The invention is clearly illustrated in the 85 accompanying drawings, in which:—

Figure 1 is a top-face view of a bag-frame with its frame-sections represented in their closed relation, and showing in connection therewith, a pair of bag-frame catches 90 made according to and embodying the principles of the present invention.

Fig. 2 is a similar view, made on an enlarged scale, of the one end of the bag-frame, the hinged frame-sections thereof and 95 the bag-frame catch being represented in an opened relation.

Fig. 3 is a longitudinal vertical section of the two frame sections in their closed relation, and of the bag-frame fastener, said 100 section being represented as taken in a vertical plane through line 3—3 in Fig. 2, looking in the direction of the arrow X; and Fig. 4 is a transverse vertical sectional representation of the two frame-sections in 105 their closed relation, and of the bag-frame catch in its locked engagement with the closed frame-sections.

Similar characters of reference are employed in all of said above described views, 110

to indicate corresponding parts. Referring now to the several figures of the drawings, the reference-character 1 indicates the outer frame-section, and 2 the inner frame-section 5 of a bag-frame, said frame-sections being preferably right-angled in cross-section, as indicated more particularly in Fig. 4 of the drawings, and the said frame-sections being provided with the usual leg-members 3 and 10 4, see Fig. 2 of the drawings, which are pivotally connected by means of a rivet or hinge-pin 5, substantially as shown in Figs. 1 and 2.

The complete structure of the bag-frame 15 fastener or locking catch is indicated by the reference-character 6, and the same consists, essentially, of a suitable shell or casing, forming a housing or box, preferably, of rectangular configuration, comprising a flat 20 top 7, a pair of end-members 8, and the longitudinally extending sides 9. Extending downwardly from the edges of the said end-members 8 are the usual clamping lugs or projections 10 by means of which the said 25 shell or casing is secured in its operative position upon the upper face of the outer frame-section 1 in the usual manner as represented in Fig. 3 of the drawings, although it will be understood that any other fastening means may be employed, if desired, for mounting and securing the bag-frame fastener in its operative position upon said frame-section 1. At or near its one end-portion, the said shell or casing is provided in 30 its flat top 7 with outwardly projecting bearing-portions or pintle-receiving members 12, in which are suitably journaled the respective 35 end-portions of a pin 13.

The reference-character 14 indicates an 40 operating lever, usually in the form of a plate, preferably bounded upon its lower surface by the longitudinally extending ribs or flanges 15, and said plate being further provided at one end with an ear 16, or the 45 like, by means of which said plate is mounted in a hinge-like manner upon said pin 13. Suitably secured within the inner portion of the said main shell or casing, and preferably, to the under surface of the top 7, by 50 means of a rivet 17, or in any other suitable manner, is a spring-like engaging member, the free end-portion 18 of which is in operative engagement with the usual short projection or stud, as 19, with which the said 55 ear 16 is provided, and extends therefrom in the manner illustrated in Fig. 3 of the drawings. As shown, the said operating lever 14 has a portion of one of its marginal flanges or ribs 15 bent inwardly, as at 20, 60 and extending in a downward direction, into and through a marginally located slot 21 formed in the top 7 of the said main shell or casing, is a lock-post or holding finger 22, preferably of the configuration represented in said Figs. 3 and 4 of the draw-

ings, and provided at its end with a suitably formed stop, as 23, adapted to engage the under surface of the top 7, when the lever 14 is brought into its raised position, as will be clearly evident from an inspection of 70 said Fig. 3 of the drawings.

The lock-post or finger 23 in this case is integrally connected with the said plate-like lever 14 at one of its marginal edge-portions, but it will be clearly understood 75 that the said lock-post or finger may be otherwise secured to said lever, it being essential, however, for the purposes of the present invention, that the said lock-post or finger is located at one side of the central 80 longitudinal axis of the said lever 14, or substantially near one of the marginal edge-portions of the said lever 14, from which it extends vertically in a downward direction, as shown in the accompanying drawings, 85 and for the purpose of maintaining the closed relation of the two frame-sections 1 and 2, of the correspondingly located receiving slots 25 and 26 in the respective frame-sections 1 and 2, as will be fully understood 90 from an inspection of the several figures of the drawings.

The operation of the bag-frame fastener hereinbefore described will be clearly understood from the illustration represented 95 in the several figures of the drawings, and any further description of the same is therefore deemed unnecessary.

The arrangement of the lock-post or finger 23 at one side of the actuating lever 14 100 permits of the arrangement of the slot 26 in the narrow inner frame-section 2, to be centrally located with relation to the width of said narrow frame-section, so that the said frame-section is not thereby weakened. 105

Furthermore, with the bag-frame fasteners as made according to the present invention, the usual hasps, riveted to the said frame-section 2, and projecting beyond the marginal edge of said frame-section, may be 110 and are entirely omitted, thereby not only cheapening the cost of construction, but also doing away with obstructing projections, in which garments may catch and become torn.

Of course, I am fully aware that changes 115 may be made in the general arrangements and combinations of the several devices and parts, as well as in the details of the construction of the said parts, without departing from the scope of the present invention 120 as set forth in the foregoing specification, and as defined in the clauses of the claim which are appended thereto. Hence, I do no limit my present invention to the exact arrangements and combinations of the several devices and parts as described in the 125 said specification, nor do I confine myself to the exact details of the construction of the said parts, as illustrated in the accompanying drawings.

I claim:—

1. In combination with the outer and inner frame-sections of a bag-frame, said inner frame-section being provided with a slot 40
 5 located centrally between the longitudinally extending marginal edges of said inner frame-section, and said outer frame-section being formed with a correspondingly located slot, a bag-frame fastener mounted upon 45
 10 said outer frame-section above the slot in said frame-section said fastener comprising a main shell provided in its upper face with a marginal slot, and a spring-controlled locking device comprising an actuating lever 50
 15 pivotally connected with said main shell, and a lock-post connected with said lever and extending vertically downwardly from one of the longitudinally extending marginal edge-portions of said lever into and being 55
 20 movably disposed in the slots of said shell and of the outer and inner frame-sections.
 2. In combination with the outer and inner frame-sections of a bag-frame, said inner frame-section being provided with a slot located centrally between the longitudinally extending marginal edges of said inner frame-section, and said outer frame-section being formed with a correspondingly located slot, a bag-frame fastener mounted upon 60
 25 said outer frame-section above the slot in said frame-section, said fastener comprising a main shell provided in its upper face with a marginal slot and a locking device comprising an actuating lever, a means of pivotal connection between said main shell and said lever, a spring secured within said shell, a stud extending from said means of 65
 30 pivot connection in engagement with said spring, said lever being provided at one of its longitudinal marginal edges with an inwardly bent and outwardly extending portion, and a lock-post connected with and extending vertically from said inwardly bent and downwardly extending portion into and through the marginal slot of said shell and the slots of said frame-sections.
 35 In testimony that I claim the invention set forth above I have hereunto set my hand 70 this 28th day of September, 1920.

JOSEPH S. ISIDOR.
